LOCK FOR BRIEFCASES AND THE LIKE

Fritz Höffgen, Iserlohn, Westphalia, Germany, assignor to Heinrich Sudhaus Sohne, Iserlohn, Germany, a corporation of Germany

Filed July 7, 1958, Ser. No. 747,086

1 Claim. (Cl. 70—67)

This invention relates to locks for briefcases, bags and similar containers.

Devices of this type usually include a keeper member in the general form of a socket for receiving a tongue including a spring latch intended to engage with an appropriate shoulder when the tongue is inserted within it. The insertable tongue ordinarily includes inner and outer plates whose spaced attaching portions, prior to application to the selected article, are firmly secured or fixed together which makes it difficult to neatly and securely fix the tongue assembly to, for example, the flap of a briefcase. That is to say, the relatively rigid spaced ends of the plates which embrace the flap of the briefcase are so firmly secured together that considerable manipulating skill is required for mounting the same on the flap by rivets. This practice also requires special tooling.

Accordingly, the present invention is primarily directed to a new form of two-part insertable tongue for socket-like keeper members wherein the tongue parts are preliminarily assembled in such a manner that the inner and outer plates are hingedly interlocked at one end and the opposite attaching ends are free to swing apart in a limited arc to more readily straddle or embrace the edge of the flap and permit of easy adjustment thereon with ultimate anchoring or securing thereto by means of a staple. In that connection, provision is made on the inner plate for shielding the inner ends of the staple prongs when the otherwise free ends of the tongue construction are fitted in position by an appropriate stapling machine.

A further object of the invention is to have the inner and outer plates forming the tongue hinged together at one end in a simple and practical manner to provide a limited range of arcuate movement of the opposite ends, which are fitted to the flap of the container.

With the above and other objects in view which will more readily appear as the nature of the invention is better understood, the same consists in the novel construction, combination and arrangement of parts, hereinafter more fully described, illustrated and claimed.

In the drawings:

Figure 1 is a front elevation of a complete lock including the keeper or socket member carried by the body of the article and the visible parts of the tongue carried by the flap.

Figure 2 is an enlarged vertical cross-sectional view taken through the tongue and a portion of the flap member, without showing the socket member, and before the tongue is secured by stapling in position.

Figure 3 is a front elevation of the outer plate of the tongue assembly.

Figure 4 is a side elevation of the tongue assembly positioned for mounting on the flap and before placing the same in the stapling mechanism.

Figure 5 is a more or less diagrammatic sectional view taken through a jig for driving the staple.

The socket member which receives the insertable tongue comprises a face plate 1 secured to the body of the

2

container by U-shaped buckle 2 which also secures the outer plate 10 in place. This plate is of substantially T-shaped formation (Fig. 3) and is provided with a central opening which exposes the spring latch 3. This latch may be controlled by a suitable locking device (not shown) actuated by a key insertable through the keyhole 4.

When the latch 3 is immobilized by the lock, the tongue will be securely held in the socket member, but when it is not under the influence of a lock it may be pushed inwardly against force of spring 33 to release the tongue from engagement with the top edge 10a of the plate 10.

Referring now more specifically to the two-part tongue illustrated in detail in Figures 2, 3 and 4, it will be seen that the same includes an inner plate 5 provided at one end with an outwardly offset lip 6 having therein a slot 7. The side edges of the plate 5 are provided with flanges having registering cutout portions or recesses 8. In addition the plate 5 has a fastening extension 9 projecting beyond the flanges at the sides thereof.

The aforesaid outer plate 10 of the tongue assembly is provided at one end with an inwardly disposed lip 11 which overlaps the lip 6 of the plate 5 (Fig. 2). The lip 11 is provided with a cleat 12 disposed substantially parallel to the inner face of the outer wall of the said outer plate 10. This cleat fits into the slot 7 of lip 6 on plate 5, thus forming a hinge-like joint between inner plate and outer plate 10. The outer plate 10 has offset side flanges which telescopically receive the flanges of the inner member 5 and have tabs 13 which project inwardly to enter the recesses 8 on the side flanges of the inner plate 5.

The above described means of connecting plates 5 and 10 permits the extensions 9 and 15 thereof respectively to move in an arc defined by the distance between the recesses 8 and the slot 7. The hinging angle of the extensions 9 and 15 of plates 5 and 10 is approximately 15° due to the fact that the ends of members 5 and 10 are loosely and hingedly interlocked, as previously indicated. This arrangement permits the extensions 9 and 15 to be separated to straddle and embrace the flap 14 thereby readily enabling the workman to adjust the tongue assembly in correct relation to the base plate and socket means on the body of the article.

As will be seen from Figure 4, the side flanges of the outer plate 10 have lugs 16 which correspond to the notches 17 in the inner plate 5.

Also the extended fastening flange 15 of outer plate 10 has two slots 18 parallel to each other, which are intended to register with the entrance to the guideways 19, whose bottom walls are directed toward each other for the purpose of guiding the tangs of the staple inwardly and shielding them so as to avoid personal injury.

From Figure 2, it may be observed that the tongue assembly may be secured to the flap of the briefcase or the like by the said U-shaped staple 20 having its prongs 21 arranged so that when the staple is fitted to extension flange 15, the said prongs will enter the slots 18, penetrate the flap 14, and register with openings 18 leading to guideways 19 so that the prongs 21 are clinched in a simultaneous operation by the press shown in Figure 5. The body portion of the staple 20 projects substantially from the outer plate 10 to constitute a finger manipulating grip for the lock casing and its latch.

For placing the staple 20 in place the jig shown in Figure 5 is used. The latter consists of a work-supporting plate 22 for supporting the tongue assembly and being cut away to fit the outline of the extension fastening flanges. This plate 22 is movable against compression springs 23 coiled about stud 24 set on base plate 25, carrying an anvil 26 having a flute 27 to accommodate

the body 20 of the staple. Anvil 26 fits into the cut away portion 28 of the upper supporting plate 22.

A press plunger 29 is positioned to drop onto supporting plate 22, striking downward onto bottom plate 5 without touching, however, the fastening flange. Near its front edge this plunger 29 has two cleats 30 which, on the downstroke, slide past lugs 16 to prevent the edge of the top plate from crimping when lugs 16 are clinched.

The forward side 31 of plunger 29 is splined and has attached to it a second plunger which is vertically 10 adjustable.

The primary position of the holding plate 22 with respect to anvil 26 is calculated in such a way that when a staple is placed into flute 27, the tips of its prongs will pass exactly through slots 18 in the flange of the outer plate belonging to a tongue supported on plate 22.

As die plungers 29 and 32 press downward, cleats 30 on plunger 29 first slide past the outside of lugs 16 and with continuing downstroke depressing work-plate 22, these cleats set the position of lugs 16 so that in the final position of the parts as determined by flange 15 seated upon anvil 26 these lugs are then completely clinched by the action of plunger 29 which is firmly pressing on plate 5 of the tongue.

The bottom corner of plunger 29 is chamfered off with respect to the bottom side thereof by a margin varying with the thickness of the leather in flap 14.

On the downstroke of plungers 29 and 32, as lugs 16 are set in position and holding plate 22 moves downward, prongs 21 of the staple are pressed through leather 14 and encountered flange 9 which is receiving pressure from plunger 32 above it. As the downstroke then continues to its end, the prongs are clinched between leather 14

and flange 9. In this end phase of the process flange 15 is seated on anvil 26.

The two plates of the tongue, prior to assembly on the article, are held by spring 33 in latch 3 in a spread-open position as limited by tab 13, so that bag flap 14 can be conveniently inserted between the two flanges 15 and 9.

I claim:

A lock for securing the flap of a briefcase or the like to keeper means on the body thereof, comprising, a lock casing including inner and outer plates whose upper portions embrace the upper face of the flap, said inner plate provided in its upper portion with a pair of laterally spaced closed depressions whose bottom walls form guideways facing the back of the flap, and said outer plate having a pair of spaced slots communicating with said depressions, said outer plate also having an opening, a spring latch in said opening and a staple including an intermediate transversely arched portion and having flat triangular end prongs whose apices register with said slots and are pressed through said slots into said guideways to shieldingly clinch the inner and outer plates together, and the inner portion of said prongs lying in and concealed by said guideways between the inner plate and the inner face of the flap, the intermediate transversely arched portion of said staple constituting an exposed outward projection to provide a substantial finger engaging manipulating portion for the locking member to withdraw it from the said keeper means.
